IRVING E. ASKE, OF MINNEAPOLIS, MINNESOTA

VAPORIZER

Application filed April 15, 1929. Serial No. 355,361.

My invention relates to vaporizers and has for its object the improvement of electric vaporizers for converting hydrocarbon fuel into hot fumes for use in starting a cold internal explosion engine, and for such other or further uses as it may be adapted to serve. It consists of the structures, combinations and arrangements of parts hereinafter described and claimed.

10 In the drawings, Fig. 1 is a central vertical section of my said invention. Fig. 2 is a horizontal section of the same approximately on the line A—B of Fig. 1. Fig. 3 is a vertical section of said invention approximately on the line C—D of Fig. 2. Fig. 4 is a side elevation of a heat insulation sheath forming part of my said invention. Fig. 5 is a front elevation of any one of the hereinafter described intermediate pads. Fig. 6 is a side elevation of the same. Fig. 7 is a front elevation of either of the hereinafter described center pads. Fig. 8 is a side elevation of the same. Fig. 9 is a front elevation of either of the hereinafter described outer pads. Fig. 10 is a grooved side elevation of the same, and Fig. 11 is a side elevation of a hereinafter described protective shell.

In the drawings, 1 is a vaporizer cup adapted to be cast upon or by any suitable means, as by ears 1^a, secured to the air-intake horn, or intake manifold of an internal explosion engine, or other fuel conductor (not shown) which it may serve, and to discharge thereto. Said cup is closed at the bottom 35 by a plug 2, through which extends a binding post 3 electrically insulated from said plug in any suitable manner, or by any suitable means, as by intervening washers 3^a of insulating material. Electrically connected at one end to the head of said post within a recess 2^a in said plug, are resistance members 4 and 5 which at their opposite ends are grounded on said cup in any suitable manner and by any suitable means.

45 The assembly of said cup, plug and resistance means is not now broadly new, but for reasons hereinafter set forth the head of the binding post or terminal screw 3 preferably has an open horizontal slot formed therein.

50 Extending into the recess in said plug is a

cylindrical heat insulating sheath 6 of any suitable heat insulating material as mica, and a concentric cylindrical protective shell 7, preferably of metal.

Heretofore, a single thick absorbent pad 55 extending diametrically across the bore of said shell, or of said sheath, has been positioned between such resistance members, filling the space between said members, and single thick absorbent pads extending across 60 the bore of said shell or of said sheath and parallel with said central pad have been positioned against the outer sides of said resistance members, respectively, for the purpose of absorbing fuel oil to be converted into vapor 65 or fumes. But heretofore the flow of oil in and through said pads has not been sufficiently rapid when the resistance members were subjected to current at five volts and the units tended to burn out when the voltage 70 was maintained at five volts carrying eighty amperes for more than a minute, even when the vaporizer cup was well supplied with fuel oil. In such case it seemed that the flow of oil was retarded by back pressure of the gases 75 rapidly generated from part of the oil by the heating members, or that the flow of oil by capillary attraction, or otherwise, was not fast enough to absorb the excess heat at five volts carrying eighty amperes and to relatively cool the resistance members. On the other hand, it is necessary to avoid chilling the resistance members by an unimpeded flow of oil when the voltage is materially reduced.

80 One object of my invention is, therefore, to increase the amount of fuel oil vaporized per second, without chilling the resistance members below a point of high efficiency, and to reduce or eliminate the tendency of the resistance members to burn out at five volts, carrying eighty amperes.

85 To effect this purpose, I position at each side of each of the resistance members a very thin absorbent member, as 8, 9, 10, 11, respectively, each preferably one-thirty second of an inch thick and extending across the bore of said cylindrical heat insulating sheath 6, which surrounds, and is spaced from said resistance members.

90 Between the central pair of said thin pads 100

which may also be referred to as the central intermediate pads, are a pair of comparatively thick absorbent central pads, 12 and 13, positioned oppositely to and parallel with each other in a plane parallel to the side faces of said central intermediate pads; said thick central pads contacting with said central intermediate pads and being spaced from each other preferably about one-eighth of an inch, more or less, to form a well 14, in which fuel oil may rise or fall freely. Said central pads extend in opposite directions from said well to the walls of said heat insulating cylinder. Each of said central and central intermediate pads extends from the top of the head of said binding post approximately to the upper ends of said resistance members.

The outward pair of said thin pads may be called the outer intermediate pads and also extend from the top of the head of said post approximately to the upper ends of said resistance members.

Against the outward side face of each of the outward intermediate pads, I position a relatively thick pad, as 15 and 16, respectively, which may be referred to as the outward pads. Said outward pads extend from the bottom of said recess in said plug, approximately to the upper ends of said resistance members, and extend laterally from the respectively adjoining outer intermediate pads to the wall of said sheath, and extend parallel with said outer intermediate pads, from the wall in one quadrant of said sheath to the wall of an adjoining quadrant thereof.

Advantage is preferably taken, however, of the curve of said sheath to provide vertical spaces or wells, as 17 and 18, between said sheath and the central parts of the relatively flat outer faces of each of said outer pads, respectively, wherein fuel oil may flow, and to form other oil spaces or corner wells, as 19, 20, 21 and 22 between the inward edges of said outward pads and the respectively adjoining walls of said sheath and the respectively adjoining outer intermediate pads.

Each of said outward pads also has formed in its inward face a vertical groove co-operating with the side of the respectively adjoining outer intermediate pads to form intermediate wells, 23 and 24, respectively, wells in which fuel oil may freely rise or fall.

Said sheath has any suitable number and form of intake ports, as 25, formed therein near its lower end adapted to register with corresponding intake ports 26 in said shell. Said intake ports in said sheath are preferably in the form of wide and highly slotted apertures, thereby permitting the registration with the ports in said shell to be more easily and cheaply effected during assembly.

Said sheath extends from a horizontal plane a short distance within the recess in said plug, to a horizontal plane slightly above the upper ends of said resistance members,

and said shell extends from the horizontal plane of the bottom of said sheath to a plane a short distance above the upper end of said sheath.

Between the upper end of said sheath and the upper end of said shell is positioned a horizontal screen 27 preferably of porcelain, which is held in position by an inwardly directed annular flange formed on the upper end of said shell. Said shell is spaced from said cup and said cup has a fuel intake port formed therein at any suitable point as at 1^b adapted to communicate with any suitable external source of supply and with the space between said cup and said shell. The fuel oil will then enter said cup and flow through said shell and insulating cylinder ports, positioned preferably opposite the wells 17 and 18, and thence into the recess in said plug and may rise in the outer wells and flow over the top of the pads and down into one or more of the several other wells, at the same time soaking through the pads by capillary attraction or under hydrostatic pressure or both, and may flow across the head of said post through said slot from the intermediate to the central well. During the heating period liquid fuel may percolate in said wells and more promptly and effectively supply oil to all the levels of said pads than could be done by capillary attraction from the bottom alone through the thick pads. By reason of the interposition of the thin pads as side walls to certain of said wells, not only is the flow of oil from the wells to the resistance members facilitated to a greater degree than where the thick pads alone were used, but the interposition of said thin pads between said wells and resistance members prevents the oil from flowing so rapidly to the resistance members as to excessively chill said members when the voltage of the heating current is reduced. If desired, transverse apertures communicating with the outer, intermediate and central wells may be formed in said pads. But such structure would tend to make the assembling operation more difficult and expensive. The pads are held firmly together by the insulating sheath which is pressed over them and fits closely, and they are made of any suitable porous and incombustible material, preferably asbestos.

What I claim is:—

1. In a vaporizer, the combination of a vaporizer cup open at one end, closed at the opposite end and provided with an intake port; a binding post extending into said cup through said closed end and insulated from the same; a pair of electric resistance members electrically connected at one end to said post within said cup and grounded on said cup; central intermediate absorbent pads positioned against the inward side faces of said resistance members; outward intermediate absorbent pads positioned against the

outward side faces of said resistance members; central absorbent pads positioned between and contacting with said central intermediate pads and extending parallel therewith, said central pads being spaced from each other diametrically of said cup to form a well between said central intermediate pads and between said central pads; a pair of outer pads positioned against the outer faces of said outer intermediate pads, said outer pads being grooved in their inward faces to form intermediate wells between said outer pads and said outer intermediate pads; a heat insulating cylinder surrounding said pads and spaced from said resistance members; a protective shell closely surrounding said cylinder and spaced for the major part of its length from said cup; and a screen positioned within said shell above said cylinder, pads and resistance members; said cylinder being spaced from said resistance members; said pads extending at their longitudinal edges to the walls of said cylinder, the outer faces of said outer pads being adapted to form chords for segments of said cylinder and in such manner to cooperate with said cylinder to form outward fuel wells; said shell and cylinder having intake ports formed therein communicating with the space between said shell and cup.

2. In a vaporizer, the combination of a cup open at one end, closed at the opposite end by a plug and having an intake port formed therein, said plug being recessed in its interior end; an electric binding post extending through said plug and insulated therefrom; a pair of parallel electric resistance members electrically connected at one end to said post and grounded at their opposite ends, said members being bent above one end; central intermediate thin absorbent pads positioned against the inward faces of said resistance members; central thick absorbent pads positioned between and contacting with said central intermediate pads and extending parallel therewith, said central pads being spaced from each other parallel to said central intermediate pads to form a central well between said central intermediate pads and between said central pads; thin outward intermediate absorbent pads positioned against the outward faces of said resistance members; thick outward absorbent pads positioned against the outward faces of said outward intermediate pads, said outward pads being grooved in their inward faces to form intermediate wells between said outward pads and said outward intermediate pads; a heat insulating cylinder open at each end and surrounding said pads and resistance members and extending into the recess in said plug and spaced from said resistance members; a protective shell surrounding said cylinder and extending above the same and extending into said recess; said pads extending at their longitudinal edges to the walls of said cylinder; said central, central intermediate and outward intermediate pads extending from the upper end of said post approximately to the plane of the upper bends of said resistance members; said outward pads extending from the bottom of said recess approximately to the plane of the upper bends of said resistance members; said shell and cylinder having intake ports formed therein, said shell being spaced from the side walls of said cup above said plug; said outward pads being adapted in part to form chords to segments of said cylinder whereby wells are formed between said outward pads and said cylinder; and a screen extending across said shell above said pads and resistance members.

3. A vaporizer characterized by a fuel cup, a pair of electric heating members mounted in said cup; a heat insulating sheath surrounding said members and spaced therefrom; a thin absorbent pad positioned against each side of each of said members; relatively thick absorbent pads positioned between the central two thin pads; a relatively thick absorbent pad positioned against the outer face of each of the outer thin pads, wells being formed between the central thin pads, and between the outer thin pads and the outer thick pads, and between the outer thick pads and said sheath; a protective shell surrounding said sheath and partly spaced from the sides of said cup, intake ports being formed in said shell and sheath.

4. A vaporizer comprising a fuel cup provided with an intake port; a pair of electric heating units erected in said cup; a heat insulating sheath surrounding said units and spaced therefrom, said sheath being spaced from said cup for a portion of its length; a plurality of thin incombustible absorbent pads within said sheath; a plurality of relatively thick incombustible absorbent pads within said sheath; said thin pads being in contact with said heating units and with the wall of said sheath; said thick pads being in contact with said thin pads and with the wall of said sheath and being spaced from said heating units; portions of some of said pads co-operating with others of said pads to form wells between them; portions of said sheath co-operating with some of said pads to form wells between them; said sheath having a fuel intake port formed therein communicating with one of said wells and with the space between said sheath and said cup, and a perforated cover for said sheath.

In testimony whereof, I hereunto affix my signature.
